UNITED STATES PATENT OFFICE.

EDGAR M. CLARK, OF NEW YORK, N. Y., AND FRANK A. HOWARD, OF ELIZABETH, NEW JERSEY, ASSIGNORS TO STANDARD DEVELOPMENT COMPANY, A CORPORATION OF DELAWARE.

ART OF FILTRATION.

Application filed December 22, 1920. Serial No. 432,562.

To all whom it may concern:

Be it known that we, EDGAR M. CLARK and FRANK A. HOWARD, citizens of the United States, residing at New York, in the county of New York and State of New York, and Elizabeth, in the county of Union and State of New Jersey, respectively, have invented a new and useful Improvement in the Art of Filtration, of which the following is a specification.

The present invention relates to the art of filtering and more particularly to the filtration of paraffine wax from chilled hydrocarbon oil. It will be clearly understood from the following description, illustrated by the accompanying drawing, in which:

Fig. 1 is a broken side elevation of a press suitable for carrying out the present invention, the cover therefor being shown in section;

Fig. 2 is a transverse sectional view on the line 2 of Fig. 1, and

Fig. 3 is an enlarged sectional view of the end portion of the press into which oil is fed, the longitudinal dimensions being on a larger scale than the vertical dimensions.

Referring more particularly to the drawings, the numerals 5, 5 indicate longitudinal supporting rods, mounted at one end upon a suitable standard 6 and at the other end upon a similar standard, (not shown). The numeral 7 indicates a stationary head or end member which is adapted to abut against the standard 6, and the numeral 8 indicates a movable head or end member at the opposite end of the press, adapted to be engaged by the end of a plunger 9, operated by hydraulic or other suitable means.

The body of the press is made up of a plurality of filter members or disks, all having substantially the same construction, as shown in detail in the drawing. Each of these filter members comprises a circular center plate 10, provided with a central opening and with substantially diametrically extending arms 11^a which rest upon the supporting bars 5 and serve to support the filter member as a whole. On each side of the plate 10 is positioned a circular wire cloth or screen 11^a and the edges of the filter disk are thickened by the imperforate rings 12^a secured to the filter member outside of the wire cloths 11, 11. A filter cloth 12^a of duck, canvas or other suitable material is placed on each side of the entire filter mem-

ber, each cloth being provided with a central opening somewhat smaller than the central opening in the plate member 10. The filter cloths on each side of each plate are sewed together tightly within the center opening of the plate, as at 13, and they are sewed together loosely or at intervals around the circumference of the plate, as at 14, 14. The adjacent filter members are of the same size, and when placed in order upon the supporting rods 5 and when pressure is applied to the end member 8, a compact unit or filter press is formed.

The end member 8 is preferably formed with an interior cavity 15 communicating with the central openings of the filter members, and a conduit member 16 opens into said hollow space to supply chilled oil to be filtered to the press. A plurality of longitudinally extending rods 17, 17 aid in the proper alignment of the members of the press and in their support.

In operation, it being assumed that the press is cold, the chilled oil to be filtered is introduced into the press through the pipe 16. It enters the space 15 in the end member 8 and from there passes through the central openings of the filter members to completely fill the spaces in the press between the filter members generally called the wax spaces. It is forced under pressure through the filter cloths, the interposition of the screen members between the rings permitting the filtered oil to drip out of the press. The wax contained in the oil is left upon the surfaces of the filter cloths. When the wax spaces of the press have been substantially filled with wax, the supply of oil thereto is stopped.

In order to remove the wax from the press, slack wax, as taken directly from the filter press, is heated to a temperature of 180° F. or above, preferably about 200° F. This heated slack wax is then forced into the press through the opening 16 into which the chilled oil was previously passed. At the same time, if desired or found advisable to aid in heating the body of metal of the press, hot slack wax may likewise be rained upon the press from the longitudinally extending spray pipe 17^a, extending the full length of the press, and suspended from suitable supports 18. The hot slack wax, together with the melted wax from the interior of the press, pass through the filter

cloths and drip from the press and are collected separately from the filtered oil. It is likewise found desirable to provide a cover, for example, of canvas, which is disposed to cover the press and the hot wax distributing pipe 17 while the latter is used to spray hot wax upon the press. Such a cover is shown in the drawings, being indicated by the numeral 19, the longitudinal rods 20 suspended by means of suitable hangers 21, 21 serving as a support for said cover.

After removal of the wax from the press, it is necessary to chill the latter before proper filtration of oil can be effected. This chilling may be accomplished by forcing either cold pressed oil or wax-bearing oil through the press. If the latter is used, it may be separately collected, again chilled 20 and passed through the press.

Although the present invention has been described in connection with the details of the specific means for carrying it out, it is not intended that these details shall be regarded as limitations upon the scope of the invention, except in so far as included in the accompanying claims.

We claim:

1. In the art of filtering wax from chilled oil, the improvement which consists in applying heated slack wax to the filtered wax, thereby melting the latter, and removing the melted wax.

2. In the art of filtering wax, the steps of forcing chilled wax-bearing oil through a filter surface, thereby depositing wax thereupon, applying heated slack wax to the deposited wax, thereby melting it, and removing the melted wax through the filter surface.

3. The method of removing wax from a filter press filled with wax which consists in forcing heated slack wax into the press, thereby melting the wax in the press and forcing the wax from the press.

4. The method of removing wax from a filter press filled with wax which consists in forcing heated slack wax into the press, thereby melting the wax in the press and forcing it out of the latter and simultaneously applying a heating fluid to the exterior of the press.

5. The method of removing wax from a filter press filled with wax which consists in forcing heated slack wax into the press, thereby melting the wax in the press and forcing it out of the latter and simultaneously applying heated slack wax to the exterior of the press.

6. In combination, a wax filter press, a spray pipe above the press and means for supplying a heated liquid to said pipe whereby the heating liquid is applied to the exterior of the press.

FRANK A. HOWARD.
EDGAR M. CLARK.
